UNITED STATES PATENT OFFICE.

MICHAEL GARLAND, OF BAY CITY, MICHIGAN.

SELF-OILING JOURNAL-BOX.

SPECIFICATION forming part of Letters Patent No. 373,283, dated November 15, 1887.

Application filed August 13, 1887. Serial No. 246,889. (No model.)

To all whom it may concern:

Be it known that I, MICHAEL GARLAND, of Bay City, in the county of Bay and State of Michigan, have invented a new and useful Improvement in Self-Oiling Journal-Boxes; and I do hereby declare that the following is a full, clear, and exact description thereof, reference being had to the accompanying drawings, making part of this application.

10 My invention relates to that type or class of self-oiling journal-boxes or pillow-blocks in which the lubricant material is fed, as the exigencies of the case may require, through the medium of a wick or wicks, which operate by 15 capillary attraction to convey the necessary quantity of oil from some suitable receptacle within the pillow-block to the periphery of the journal or shaft, which works within the box of said block. Heretofore several contrivances have been devised involving this 20 general principle of construction; but in all of them the oil-receptacle has been located either above or below the journal or shaft, and the contrivances have been such as to involve more 25 or less complexity of structure and inefficiency or unreliability of action.

I propose to provide for use an automatic or self-oiling journal-box which shall be extremely simple of construction and at the same 30 time perfectly efficient and reliable in its operation; and to this end and object my invention consists in the novel construction of self-oiling box hereinafter more fully described, and more particularly pointed out and distinctly defined in the claim of this specification.

To enable those skilled in the art to which my invention relates to understand and practice the same, I will now proceed to more fully 40 describe it, referring by letters to the accompanying drawings, which form part of this specification, and in which I have shown my invention carried out in that form in which I have so far successfully practiced it, and which 45 is about the best form now known to me.

In the drawings, Figure 1 is an end view or elevation of pillow-block and shaft or journal made according to my invention. Fig. 2 is a top view of the same. Fig. 3 is a view looking down on top of the contrivance, but with the cap or upper half of the box removed.

Fig. 4 is a vertical cross-section at the line *xx* of Fig. 2.

In the several figures the same parts will be found designated by the same letters of reference.

a is the lower half or main portion of the pillow-block or box-casting, which may be made in about the form and of about the proportion shown, and which is supposed to be 60 securely bolted onto its supporting surface or foundation by means of suitable bolts, *b*, in about the usual manner, while *a⁵* represents the cap or upper half of the box or pillow-block, which, when in place, is secured or held in the 65 usual manner by means of anchor-bolts *c*, which are inserted within the lower half or base, *a*, of the pillow-block, and are provided at their upper ends with the usual nuts, *d*, all as clearly shown.

E represents part of a shaft or journal that is arranged to run in the journal-box, which latter, as usual, has the two halves *a* and *a⁵*, provided with the usual Babbitt metal- or other bearings, (shown at *e*.) These Babbitt 75 metals or half-bearings, which are, as usual, cast in the iron halves of the pillow-block or box proper, instead of being held in place by means of anchorages formed by chiseling recesses or depressions in the cast-iron parts and 80 then running the Babbitt metal into such depressions, are securely held in place by anchorages composed of portions of the Babbitt metal, which are cast or run into pockets or depressions *a⁶*, that are formed in the cast-iron parts 85 in the casting of the latter. The shape and locations of these anchorage pockets or depressions *a⁶* are clearly shown in the drawings.

At each side of the journal and within the casting *a*, composing the main or lower part of the pillow-block, are formed oil chambers or receptacles *a²*, which are separated, as seen, from the Babbitt-metal bearings *e* by thin partition-like portions *f* of the casting *a*, which partition-like portions *f* of said casting are perforated each with two holes, through which the piece of wick *a³* passes in the manner shown, the said wick having its uppermost straight portion arranged to lie in contact with the greater part of the bearing-surface of the journal *E* and its drooping and outwardly-projecting portion hanging down within the oil cham-

bers or receptacles a^2 in such manner that by capillary attraction the oil or other lubricant in said chambers will be continually fed by said wicks to the bearing-surface of the journal E just in proportion as said journal may require lubrication.

What I claim as new, and desire to secure by Letters Patent, is—

A journal-box having oil-receptacles a^2 , arranged as specified, and provided with capil-

lary feeders a^3 , each of which has its body portion arranged within a longitudinal recess in the bearing and in contact with the shaft or journal, and also has its ends depending into one of said oil-receptacles, all as hereinbefore set forth.

MICHAEL GARLAND.
